UNITED STATES PATENT OFFICE.

THOMAS D. DALLMEYER, OF PITTSBURGH, PENNSYLVANIA.

RAIL-ANCHOR.

1,215,780.

Specification of Letters Patent. Patented Feb. 13, 1917.

Application filed December 28, 1914. Serial No. 879,285.

To all whom it may concern:

Be it known that I, THOMAS D. DALLMEYER, a citizen of the United States, and resident of Pittsburgh, in the county of Allegheny and State of Pennsylvania, have invented a new and useful Improvement in Rail-Anchors; and I do hereby declare the following to be a full, clear, and exact description thereof.

10 My invention relates to rail-anchors, or anti-creeping devices for railroad-rails.

The object of my invention is to provide a one-piece, self-locking rail-anchor which will grip the rail with great tenacity and 15 prevent the creeping of the same.

To these ends my invention comprises, generally stated, a rail-anchor formed of a single piece of metal having the proper amount of resiliency, the anchor having inwardly turned ends engaging opposite flanges of the rail, one of the inwardly extending ends having a notch or recess formed therein normally out of line with the flange of the rail, when not in gripping 25 engagement therewith, and adapted to be brought into gripping engagement with the rail flange by forcing the end portion down and springing the end portion against the flange with the flange entering said recess or engaging the shoulder formed by said recess.

In the accompanying drawing, Figure 1 is a cross-section of a rail showing my improved rail-anchor applied thereto but not 35 gripping the rail; Fig. 2 is a like view showing it gripping the rail; and Fig. 3 is an end view showing the rail-anchor in engagement with the tie.

In the drawing, the numeral 2 designates 40 a rail of ordinary cross-section with the head 3 and the flanges 4. My improved rail-anchor is made of one piece of metal having the proper amount of spring or resiliency. It consists of the body-portion 5 with the inwardly bent ends 6 and 7. The end-portion 7 projects up above the end-portion 6 when the rail-anchor is applied to the rail but before being gripped thereby, and said end-portion 7 has the notch or recess 8 which is above the edge of the flange, 45 said recess forming the shoulder 8^a. The rail-anchor is formed with the slight bulge 9 and when the anchor is applied to the rail, as indicated in Fig. 1, the inwardly ex-

tending end 6 fits over the flange of the 55 rail and may be driven into position with the bulge 9 engaging the bottom of the rail, said inwardly extending end and said bulge forming a jaw to grip the flange. In order to force the anchor into gripping position, 60 the inwardly extending portion 7 is forced downwardly by a sledge or in any other suitable manner, the metal springing outwardly to pass the flange, and when the notch 8 comes in line with the edge of the flange it 65 springs inwardly and engages the flange as indicated in Fig. 2 by a self-locking engagement. The shoulder 8^a engages the lower face of the rail base, holding the anchor in position. When the shoulder has 70 been brought into engagement with the rail base, the bulge 9 merely bears against the lower face of the rail base but without any appreciable pressure as the springing of the anchor into position by the downward 75 movement of the end portion 7 the anchor is securely clamped in position without the assistance of the bulge 9. In this manner, the device is quickly applied and the gripping action brought into play by the simple 80 blow of a hammer, and when the rail-anchor is once applied to grip the rail, as in Fig. 2, it grips the rail with great tenacity and takes hold securely against movement.

The body-portion 5 of the anchor engages 85 the tie 10, and so prevents the creeping of the rail.

The device being formed of one piece can be readily formed in dies and the cost of manufacture of same is reduced to a minimum. 90

What I claim is:

1. A rail-anchor formed of a single piece of spring-metal having inwardly extending ends, one end fitting over the flange at one 95 side of the rail, and the opposite end having a notch normally above the flange and adapted to be forced downwardly to bring said notch into engagement with the flange of the rail.

2. A rail-anchor formed of a single piece of spring-metal having inwardly extending ends, one end fitting over the adjacent flange, the body-portion having a bulge engaging the bottom of the rail adjacent to 105 said end-portion, and the opposite end having a notch normally above its adjacent flange and adapted to be forced downwardly

to bring said notch into engagement with the flange of the rail on that side.

3. A rail anchor formed of a single piece of spring metal having inwardly-extending ends, one end fitting over the flange at one side of the rail, and the opposite end having a shoulder normally above the flange and adapted to be forced downwardly to

bring said shoulder into engagement with the lower face of the rail flange.

In testimony whereof, I the said THOMAS D. DALLMEYER have hereunto set my hand.

THOMAS D. DALLMEYER.
